FIG. 3.

A.C. Sheller. INVENTOR.

BY

Lucy Lacy ATTORNEY.

UNITED STATES PATENT OFFICE.

ALBERT G. SHELLER, OF CLAYSVILLE, PENNSYLVANIA.

TELEPHONE ATTACHMENT.

1,404,800.

Specification of Letters Patent. Patented Jan. 31, 1922.

Application filed July 20, 1920. Serial No. 397,779.

To all whom it may concern:

Be it known that I, ALBERT G. SHELLER, a citizen of the United States, residing at Claysville, in the county of Washington and 5 State of Pennsylvania, have invented certain new and useful Improvements in Telephone Attachments, of which the following is a specification.

This invention relates to a telephone attachment adapted for use on party lines for 10 the purpose of detecting eaves-dropping or cutting-in on the wire by unauthorized parties.

It often happens that, on party telephone 15 lines where several parties are included in the same line, curious and unscrupulous persons will listen-in on the conversation. It is the object of this invention to provide a means for attachment to the telephone instruments whereby such listening may be detected 20 and the guilty party identified.

Accordingly, the invention specifically provides a bell and transmitter attachment for telephones actuated by the lifting of the 25 receiver hook so that the sounding of the bell is carried along the wire and by providing different parties with different sounding bells the guilty party may be easily located.

In the drawings:

30 Figure 1 is a perspective view of a telephone instrument having the invention incorporated therein;

Fig. 2 is a detail enlargement, in side elevation, of the striker mechanism for the 35 alarm bell;

Fig. 3 is a horizontal section on the line 3—3 of Fig. 1.

In detail:

The invention, as herein shown, is applied 40 to the usual box type telephone instrument indicated at A and having the usual transmitter 1, receiver 2 and receiver hook 3. Mounted at the head piece of the telephone is a supplemental transmitter 4 connected 45 with the wires of the main transmitter 1. Situated approximate the transmitter 4 is a chime or bell 5 which may either be of the coil type or the usual bell type. A trans- 50 verse shaft 6 is mounted in bearings 7 and carries a striker arm 8 having a suitable striker end 9 so that oscillation of the trans- 55 verse shaft 6 will cause the striker to engage its striker end 9 with the chime or bell 5 to sound the same, which sound will be received in the transmitter 4 and carried along the line so that parties talking on the line will

know that another party whose bell they can identify by sound is listening-in on the conversation.

For actuating the bell at the proper time 60 the transverse shaft 6 carries a spring 10 coiled therearound and having one end 11 engaged with one of the brackets or supports 7 and the other end engaged around a detent pin 12. Side frames 13 and 14 of triangular 65 formation and secured in place by screws 15 running through ears 16 provide a rigid support for the shaft 6 and the parts cooperat- 70 ing therewith, said frames being connected by cross bars 17 and 18. The cross bars 17 and 18 carry a vertical guide bracket 19 which has guide straps 20 receiving and 75 guiding the reciprocable member 21 notched as at 22 for engagement with the detent pin 12, the guide bracket 19 having a similar 80 notch 23 to permit play of the pin. The lower end of the reciprocable bar 21 is pro- 85 vided with a longitudinal slot 24 through which the receiver hook 3 passes so that said bar will follow the movements of the hook. 90

The removal of the receiver 2 from the receiver hook arm permits the spring-tensioned receiver hook arm 3 to elevate in the usual manner with the result that it carries with it the reciprocable bar 21. As the said 95 reciprocable bar moves upwardly, the detent pin 12 is raised and, by reason of its engagement with the inclined wall of the notch 23, is gradually pushed out of the notch 22, as shown in Fig. 2, and upon clearing the said notch 22 is returned suddenly, under the tension of spring 10, to the base of the notch 23 thereby causing the striker 8 to sound the chime 5, the sound being carried into the line by the transmitter 4. Upon 100 the replacing of the receiver upon the hook arm 3, the reciprocable member 21 is re- turned to its normal position and the detent pin 12 springs into engagement with the notch 22.

It is to be noted that the mechanism of the attachment is entirely enclosed thereby preventing tampering with the same by unauthorized parties.

I claim:

1. In combination with a telephone having a receiver and transmitter, a receiver hook carrying the receiver, a bell having a striker, and separate reciprocable means engaging with the receiver hook and cooperat- 110 ing with the bell striker for actuating the latter, and a cam adapted to release said

striker from engagement with said reciprocable means.

2. In combination with a telephone having a receiver and transmitter, a receiver hook carrying the receiver, a bell having a striker, and notched reciprocable means engaging with the receiver hook and cooperating with the bell striker for actuating the latter in one direction, other means for actuating said striker in the opposite direction, and a cam adapted to release said striker from engagement with said reciprocable means.

3. The combination of a telephone set, of a supplemental transmitter, an audible signal including a bell and a striker arranged adjacent said supplemental transmitter, a slide positively engaged with the receiver hook of the telephone set, a frame in which said striker is mounted to oscillate, a guide for said slide on said frame, an element on

said striker engaging with said slide, means for actuating said striker in opposition to said slide, and means for disengaging said element from said slide at a definite point 25 of its travel.

4. The combination of a telephone set, of a supplemental transmitter, an audible signal including a bell and a striker arranged adjacent said supplemental transmitter, a 30 slide positively engaged with the receiver hook of the telephone set, a frame in which said striker is mounted to oscillate, a guide for said slide on said frame, an element on said striker engaging with said slide, means for actuating said striker in opposition to said slide, and a wedge on said frame adapted to co-operate with said element to disengage the latter from said slide at a definite point of its travel. 40

In testimony whereof I affix my signature.
ALBERT G. SHELLER. [L.S.]
